UNITED STATES PATENT OFFICE.

GEORGE KREMENTZ, OF NEWARK, NEW JERSEY.

COLLAR-BUTTON.

SPECIFICATION forming part of Letters Patent No. 315,418, dated April 7, 1885.

Application filed February 16, 1885. (No model.)

To all whom it may concern:

Be it known that I, GEORGE KREMENTZ, of Newark, Essex county, New Jersey, have invented a new and Improved Collar-Button, of which the following is a full, clear, and exact description.

This invention relates to certain new and useful improvements in the collar-button for which United States Letters Patent No. 298,303, 10 were issued to me on the 6th day of May, 1884.

Reference is to be had to the accompanying drawings, forming part of this specification, in which similar letters of reference indicate corresponding parts in all the figures.

15 Figure 1 is a cross-sectional elevation of the button shown and described in my Letters Patent No. 298,303. Fig. 2 is a side view of my improved collar-button. Fig. 3 is a cross-sectional view of the same on the line *xx*, Fig. 2.

20 The button A (shown in Fig. 1) has a hollow stem, B, and head C, all made in one piece with the base-plate D.

In order to give the button, which is made by a machine, the appearance of a hand-made 25 button, I press the bottom and top layers of the head together so that they are in contact, as shown in Fig. 3; but the edges of the head are bent and curved down so as to form a rounded head and to prevent the edges of the 30 head from cutting into the skin in case the

button is tilted and laid over against the arm or wrist with the shirt-sleeve.

I am aware that busk-fastenings and metal rivets have been made by forming a hollow metal shank or stem, and then flattening down or upsetting the end of the same to form a head, which head, however, is flat, and has its sharp edges projecting laterally from the stem, which I desire to avoid for the reasons stated.

I do not form the head by upsetting or flattening the end of the stem; but the hollow head is first formed by contracting the stem, and then the top and bottom of the head are pressed together.

Having thus described my invention, I claim 45 as new and desire to secure by Letters Patent—

As an improved article of manufacture, a collar-button having a hollow stem formed on a base, a head on the stem, the top and bottom layers of the head being pressed together to 50 be in contact, and the edges of the head being bent down to form a curved top surface for the head, the head, stem, and base being formed of a single piece of sheet metal, substantially as herein shown and described.

GEORGE KREMENTZ.
